UNITED STATES PATENT OFFICE.

WILLARD F. MAIN, OF IOWA CITY, IOWA.

SURGICAL APPLIANCE.

No. 798,611.

Specification of Letters Patent.

Patented Sept. 5, 1905.

Application filed June 16, 1903. Serial No. 161,724.

To all whom it may concern:

Be it known that I, WILLARD F. MAIN, a citizen of the United States, residing at Iowa City, in the county of Johnson and State of Iowa, have invented certain new and useful Improvements in Surgical Appliances, of which the following is a specification.

My invention relates to that class of surgical appliances intended to prevent bed-wetting; and it consists of a receptacle having spring-terminals in circuit with a battery and alarm and separated in use by a soluble wafer which on being dissolved allows the terminals to come together, complete a circuit, and sound an alarm, as fully set forth hereinafter and as illustrated in the accompanying drawings, in which—

Figure 1 is a perspective view of my improved appliance; Fig. 2, a longitudinal section of the same detached from the supporting-apron; Fig. 3, an outside view of the receptacle detached from the other parts.

The receptacle A is of rubber or other material which will not conduct an electric current and contains two spring-terminals 1 1, which normally are in contact and are then in circuit with a battery B through suitable flexible conductors 2, including a switch 3 and an electric bell or other alarm 4, the battery-switch and alarm preferably in or supported by a casing 5. The terminals 1 1 are coated except at the ends, so that the presence of a fluid will not complete a circuit between them when separated, and such separation is secured by a soluble wafer 6. It will be seen that so long as the receptacle is empty and the wafer in place the circuit will be broken, but the presence of a liquid in the receptacle will quickly dissolve the wafer, when the terminals will come into contact, complete the circuit, and sound an alarm until the switch is shifted to break the circuit.

The appliance thus described may be secured to the body of the user in any suitable manner. For instance, the mouth of the receptacle may be provided with a flaring flange 7, of rubber or other soft elastic material which will avoid abrading or wounding the skin and secure a close joint, and the receptacle may be held in place by connecting thereto clamps 8, which may engage the under-clothing. Preferably, however, a small apron C is secured to the person by straps or bands 9 10, and through an opening x the casing A is passed, leaving the flange 7 inside the apron, and the clamps 8 are clamped to this apron. As thus applied the receptacle will be held

firmlly in place, but without discomfort to the wearer and without danger of the liquid escaping from the receptacle, the flexible conductors 2 extending to the casing, which may be arranged in any position accessible from the bed. On the sounding of the alarm the wearer is at once awakened, and in course of time the habit of awakening as soon as any desire of emission is felt will be established.

To adjust the clamps 8, each is connected to a band 14, preferably elastic, which passes first beneath and then over the bars of a slotted plate 12 and then beneath the plate. The plate 12 is secured in position on the receptacle by screws 13, which may be loosened to permit the adjustment of the band to increase or decrease the tension. It will be seen that the elastic bands will draw the receptacle back and press the flange 7 tightly against the person of the wearer.

It will be evident that the forms and proportions of the parts and means of connection may be varied without departing from the main features of my invention.

Without limiting myself to the construction and arrangement shown, I claim—

1. In a device of the character described, the combination of a receptacle, spring-terminals therein, an alarm, an electric circuit including said terminals and alarm, and means for normally holding said terminals separated, said means being soluble in the presence of a liquid, substantially as and for the purpose described.

2. The combination of the receptacle A, its spring-terminals adapted to clamp a soluble wafer, a battery and alarm, and flexible conductors including the terminals, battery and alarm, substantially as set forth.

3. In a device of the character described, the combination with a receptacle closed at one end and open at the other, spring-terminals in said receptacle at its closed end, an alarm, an electric circuit including said terminals and alarm, means for normally holding said terminals separated, said means being soluble in the presence of a liquid, and means for securing the receptacle to the person of the wearer, substantially as described.

In testimony whereof I have signed my name to this specification in the presence of two subscribing witnesses.

WILLARD F. MAIN.
